US00D582550S

(12) **United States Design Patent**
Baxter et al.

(10) **Patent No.:** **US D582,550 S**
(45) **Date of Patent:** **** Dec. 9, 2008**

(54) **OVAL TAPERING BLUNT CANNULA
PROXIMAL PORTION**

(75) Inventors: **Charles S. Baxter**, Worthington, OH (US); **Theodore J. Mosler**, Raleigh, NC (US); **Charles R. Patzer**, Columbus, OH (US)

(73) Assignee: **Smiths Medical ASD, Inc.**, Rockland, MA (US)

(**) Term: **14 Years**

(21) Appl. No.: **29/303,394**

(22) Filed: **Feb. 7, 2008**

(57) **CLAIM**

The ornamental design for an oval tapering blunt cannula proximal portion, as shown and described.

DESCRIPTION

FIG. 1 is an upper perspective view of our new, original and ornamental design;

FIG. 2 is a lower perspective view thereof;

FIG. 3 is a front elevational view thereof, the rear elevational view being a mirror image thereof;

FIG. 4 is a right side elevational view thereof, the left side elevational view being a mirror image thereof;

FIG. 5 is a top plan view thereof; and,

FIG. 6 is a bottom plan view thereof.

The structure shown in phantom is for illustrative purposes only and forms no part of the claimed design.
